DESIGN FOR A DOLL CARRIAGE OR SIMILAR ARTICLE

Willard T. MacCallum, New York, N. Y., assignor to Sturdy Toy Makers, Inc., New York, N. Y., a corporation of New York

Application November 29, 1944, Serial No. 116,604

Term of patent 3½ years

(Cl. D34—15)

To all whom it may concern:

Be it known that Willard T. MacCallum, citizen of United States and resident of New York city, in the county of New York and State of New York, has invented a new, original, and ornamental Design for a Doll Carriage or Similar Article, of which the following is a specification, reference being had to the accompanying drawings, forming part thereof, and in which,

Fig. 1 is a side view of the doll carriage, embodying my new design;

Fig. 2 is a top view thereof; and

Fig. 3 is a front end view thereof.

I claim:

The ornamental design for a doll carriage or similar article, substantially as shown.

WILLARD T. MACCALLUM.
